UNITED STATES PATENT OFFICE

110,088

DESIGN FOR A DRESS

Max Frankel, New York, N. Y.

Application May 13, 1938, Serial No. 77,163

Term of patent 3½ years

To all whom it may concern:

Be it known that I, Max Frankel, a citizen of the United States and residing in Manhattan, in the city, county, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The flower at the shoulder is permanently attached.

I claim:

The ornamental design for a dress substantially as shown and described.

MAX FRANKEL.
